UNITED STATES PATENT OFFICE.

ADOLF HAZY, OF NEW YORK, N. Y.

LOCK.

SPECIFICATION forming part of Letters Patent No. 735,095, dated August 4, 1903.

Application filed January 2, 1903. Serial No. 137,453. (No model.)

To all whom it may concern:

Be it known that I, ADOLF HAZY, a citizen of the United States, residing in New York city, county and State of New York, have invented a new and useful Improvement in Door-Locks, of which the following is a specification.

The advantage of the lock lies in the fact that it will resist force applied in any and all directions except that proper force intended to be used in unlocking it—that is, a door provided with this improved bolt can be opened only from the inside. It is an effectual barrier against all attempts to force the lock from the outside.

The device is simple in construction and cheap to manufacture.

To assist in explaining the invention, reference is made to the accompanying drawings, in which similar letters refer to similar parts.

Figure 1 is a plan view of the locking device, one side of the casing being removed. Fig. 2 is another plan view showing the bolts shot into their locking positions. Fig. 3 is a sectional view taken through the line 1 1 of Fig. 1. Fig. 4 is a sectional view taken through the line 2 2 of Fig. 1.

A is the casing.

B is the rectangular opening in casing A to permit of the lateral sliding of the guide-block C. This guide-block has an aperture to receive the screw-pin D, which passes through it and secures a sliding block E.

F is a symmetrical double-armed lever, which has for its axis a pin G. The lever has at the end of each arm lugs H, which project into the aperture I of the bolt J.

K is a shell incasing the bolt J. In shell K there is an opening L to permit of the entrance of the lug H into the aperture of the bolt J.

The operation of the mechanism is as follows: Fig. 2 shows the bolts in their locked position. To draw the bolts, it is necessary simply to slide the screw D to the left, thus

raising one arm of the lever H and lowering the other arm, which at the same time withdraws the bolts within their shells.

Though the bolt is primarily designed for use as a lateral lock, it may also be employed to engage the casing of the frame above the door, or it may be used to bolt the door to the floor, or it may be adapted for use on a safe. Its main use, however, is for the night-door of a dwelling. In this case the double lock is unnecessary and one of the bolts J may be removed from the casing or the device may be manufactured without it.

Particular attention is directed to the fact that when in its locked position no pressure on any part of the bolt J extending beyond the casing is sufficient to force the bolt back to its position in the shell K. This condition is secured by the pressure of the arms of the sliding block E against the arms of the lever F.

Thus having described my improvement, what I claim as my invention, and desire to secure by Letters Patent, is—

1. The locking device consisting of a combination of a frame having an aperture, a guide-block adapted to move in said aperture, a pin constructed so as to pass through the guide-block, a sliding block connected with the said pin and so formed as to have its arms move in contact with the arms of the lever, a symmetrical double-armed lever moved by said sliding block, a bolt and means for connecting the bolt and ends of the lever.

2. The locking device consisting of a combination of a frame, a guide-block, adapted to move in an aperture of said frame, a pin passing through the block, a lever adapted to move the bolts, bolts attached to a lever, and a sliding block connected with the pin for moving the lever, substantially as described.

3. A locking device consisting of a combination of a frame and aperture in said frame, a guide-block to move in said aperture, a symmetrical double-armed lever, means for sliding the guide-block, and elevating and

lowering simultaneously the arms of a lever, a sliding bolt or bolts connected with the arms of the lever, substantially as described.

4. In a locking device, the combination of 5 a symmetrical double-armed lever, a sliding block adapted to move in contact with the arms of the lever and constructed so as to move the lever, means for connecting the lever with a bolt or bolts, and bolt or bolts con-

nected with the lever, substantially as described.

In witness whereof I have hereunto set my hand, in the presence of two subscribing witnesses, this 30th day of December, 1902.

ADOLF HAZY.
